UNITED STATES PATENT OFFICE

91,716

DESIGN FOR A BOILER

Emert J. Lattner, Cedar Rapids, Iowa

Application July 1, 1933, Serial No. 48,618

Term of patent 14 years

To all whom it may concern:

Be it known that I, EMERT J. LATTNER, a citizen of the United States, residing at Cedar Rapids, in the county of Linn and State of Iowa, have invented a new, original, and ornamental Design for a Boiler, of which the following is a specification, reference being had to the accompanying drawing, forming part thereof.

Figure 1 is a front quartering view in perspective of a boiler showing my new design.

Figure 2 is a view in perspective of the front

portion of the boiler shown in Figure 1 but taken from the opposite quarter, and

Figure 3 is a view in perspective of the rear of the boiler. In this view the front portion has been broken away.

I claim:—

The ornamental design for a boiler as shown and described.

In witness whereof, I hereunto subscribe my name this 28th day of June, 1933.

EMERT J. LATTNER.
